UNITED STATES PATENT OFFICE.

WILLIAM STRIMPLE, OF JERSEY CITY, NEW JERSEY.

BRIDGE-WARNING.

1,360,992.

Specification of Letters Patent. Patented Nov. 30, 1920.

Application filed May 29, 1920. Serial No. 385,221.

To all whom it may concern:

Be it known that I, WILLIAM STRIMPLE, a citizen of the United States, and a resident of Jersey City, county of Hudson, and State 5 of New Jersey, have invented a new and Improved Bridge-Warning, of which the following is a full, clear, and exact description.

This invention relates to bridge warnings, 10 and has reference more particularly to bridge warnings consisting of a plurality of rigid suspended members positioned above a railroad track.

As commonly practised, a number of wires 15 or ropes are suspended from a cross arm so as to hang over a railroad track so that a man riding on top of a railroad car will be struck in the face by these ropes or "ticklers" which will indicate to the man on the car 20 that he is approaching a bridge which he must avoid by stooping in order to pass thereunder. It frequently happens that these ropes become wet in the winter time, and freeze up so that the man on the car 25 is dealt a heavy blow by the rope. The wires or suspended ropes are also bent out of shape and thrown up under the cross arm by the railroad man or by the exhaust of the engine, so that a crew of men must be 30 kept at work keeping these bridge warnings in condition.

An object of this invention, therefore, is to provide bridge warning members which are rigid so that they may not be bent or 35 twisted out of shape, and which will not absorb water and freeze in the winter time.

Reference is to be had to the accompanying drawings forming a part of this specification, in which it is understood that the drawings 40 illustrate only one form of the invention with certain modifications, and in which—

Figure 1 is an elevation of my improved bridge warning.

Fig. 2 is a fragmentary detail view of the bridge warning on a large scale.

Fig. 3 is a detail view on a large scale of one of the suspended members with parts broken away to disclose the construction.

Fig. 4 is a fragmentary elevation on a large scale of one of the suspended members.

Fig. 5 is an elevation of a modified form of my bridge warning adapted to be used on several tracks.

Fig. 6 is a sectional view through the 55 bridge warning on the line 6—6 of Fig. 5.

Referring to the accompanying drawing by numerals, 10 indicates an upright standard or support. A cross arm 12 is secured to the standard 10 by bolts 13 secured to a collar 14, said collar encircling the standard 10. An oblique brace 15 is secured at its upper end to the cross arm 12 by a collar 16 and at its lower end to the standard 10 by a collar 17. The cable 11 extends from the bottom of the standard 10, to which it is fastened in any suitable manner, over the curved top of the standard 10, out to the end of the cross arm 12, whereby the cross arm 12 is stayed by the cable 11 in conjunction with the brace 15 to effectively carry the weight of the bridge warning.

A plurality of eye bolts 18 are secured at intervals to the cross arm 12, and a rod 19 passes through said eye bolts and is secured 75 in place by collars 20. A plurality of "tickler" heads 21 are suspended at intervals on the rod 19, and are spaced apart by collars 22. The lower ends of the heads 21 are provided with a recess 23 which is 80 adapted to receive a slat or "tickler" 24, said "tickler" being preferably constructed rectangular in cross section, and being made of light-weight wood which cannot be bent and will not absorb moisture and freeze in the 85 winter time. A pin 24_a passes through the lower end of the head 21 and the upper end of the "tickler" 24 so as to hold said tickler in position in the recess 23.

When the bridge warnings are placed over 90 a number of tracks, a cable 25 is stretched between poles 26 so as to be positioned transversely of said tracks, and said cable 25 is further supported by a bracing cable 27 connected to the cable 25 by links 28. A plurality of clamping members are secured to the cable 25 and to the rods 19_a, and these clamping members consist of a pair of metal strips 29, registering arcuate sections 30 at each end which coöperate to embrace 95 the cable 25 and rod 19_a, and said strips 29 are held together at their extreme ends by bolts 31.

I would state in conclusion that while the illustrated example constitutes a practical 105 embodiment of my invention, I do not limit myself strictly to the mechanical details herein illustrated, since manifestly the same

can be considerably varied without departure from the spirit of the invention as defined in the appended claim.

Having thus described my invention, I
5 claim as new and desire to secure by Letters
Patent:

In a bridge warning, a rod, means for sup-

porting said rod above a railroad track, a plurality of spaced collars on said rod, and a plurality of rigid, suspended members 10 pivotally mounted to said rod and spaced apart by said spacing collars.

WILLIAM STRIMPLE.
